UNITED STATES PATENT OFFICE.

FRANCIS C. MASON AND GUY L. SINTZ, OF GRAND RAPIDS, MICHIGAN, ASSIGNORS, BY DIRECT AND MESNE ASSIGNMENTS, TO NORMAN W. CHAMBERLIN, OF GRAND RAPIDS, MICHIGAN.

IGNITION-TIMER FOR INTERNAL-COMBUSTION ENGINES.

No. 906,729.

Specification of Letters Patent.

Patented Dec. 15, 1908.

Application filed October 26, 1906. Serial No. 340,710.

To all whom it may concern:

Be it known that we, FRANCIS C. MASON and GUY L. SINTZ, each being a citizen of the United States of America, residing at Grand Rapids, in the county of Kent and State of Michigan, have invented certain new and useful Improvements in Ignition-Timers for Internal-Combustion Engines; and we do hereby declare the following to be a full, clear, and exact description of the invention, such as will enable others skilled in the art to which it appertains to make and use the same.

Our invention relates to improvements in ignition timers, for internal combustion engines, the charge in which is fired by electric spark mechanism; and its object is to provide a reliable device for simultaneously adjusting the time of the ignition in a number of cylinders; to provide a reliable device for the purpose, not likely to get out of order, and to provide the same with various new and useful features hereinafter more fully described and particularly pointed out in the claims.

Our device consists essentially of a rotating head arranged transversely of a shaft and adapted to rotate synchronously with the engine, and having a transversely movable member provided with a rolling contact to successively close the electric circuits that operate the firing mechanism, said rotating head being inclosed in a case, within which is a ring of insulating material traversed by said rolling contact and in which at regular intervals is inserted the terminals of the electric circuits, said terminals being spaced apart equidistant and in number corresponding to the number of the cylinders of the engine to which the device may be applied. The case having these described devices therein is adjustable rotatively about the axis of the rotating member whereby the contact will engage the various terminals earlier or later in the course of its revolution according to the adjustment of the case.

Our invention further consists in the particular arrangement and combination of these various features whereby the same are not likely to become worn; to get out of order, or to become displaced or loosened by the vibration and impact of the contact, and in the various details of construction and arrangement hereinafter more fully described, as will more fully appear by reference to the accompanying drawings, in which:

Figure 1. is a front elevation of a device embodying our invention with parts broken away to show the construction; Fig. 2. a vertical section of the same on the line 2—2 of Fig. 1.

Like numbers refer to like parts in both of the figures.

1 represents a cylindrical case closed at the front by a transparent disk 2, preferably of mica, and detachably secured in place by means of a screw threaded ring 3. The back of the case is closed and provided with a boss 4 forming a bearing in which is journaled a short shaft 5 having a socket at its outer end to receive any connecting means to rotate the shaft synchronously with the movement of the engine and in proper time to perform one revolution of this shaft to each complete cycle of operation of the engine. 6 is a screw-threaded stem inserted in the inner end of this shaft on which stem and within the case, is a transverse tubular head 7 in which is mounted the longitudinally movable shank 8 of a yoke 9 in which yoke is journaled a rolling contact 13, which contact traverses the interior of a ring 14 of insulating material, preferably of hard fiber, inserted in the case and contacting the interior of the same. At equal intervals on this case are radial bosses 15 equal in number to the number of the cylinders of the engine, four being shown. In these bosses are inserted tubes 19 of insulating material and engaging the outer ends of the bosses are insulating washers 20. Terminals to which the various electric circuits are attached are inserted in the axis of these bosses and consist of metallic bolts 16 having heads 17 embedded in the insulating ring 14 and projecting slightly therefrom on the inner surface of the same. These bolts are provided on their outer ends with jam nuts 18 between which the wires of the respective circuits (not shown) are connected to the bolts. These bolts also serve to securely hold the parts in place. An arm 21 on the case 1 serves to hold the same from rotating and to adjust the case about the axis of the shaft 5, which adjustment determines the earlier or later contact of the roller 13 with the heads 17 of the terminals. A rod 22 connects the arm with any suitable adjusting means. A spring 10 surrounds the shank 8 and yieldingly forces the roller 13 in contact with the inner surface of the insulation 14 and heads 17 of the terminals. A pin 11 in

this shank engages and traverses a slot 12 in the head 7 and thus maintains the axis of the roller 13 parallel with the axis of the shaft.

The disk 2 serves to inclose and protect the various parts from dust or other outside interference with its operation.

It will be noted that the terminals contacted by the roller 13 are embedded in the insulating material and are not likely to be

displaced or loosened by the hammering action due to the rapid rotation of the roller around the interior of the case. So also all the insulating material is firmly clamped in place by the jam nuts on the outer end of the bolts 16 and thus secured against any looseness or displacement by any variation due to the contact of the roller 13 with the terminals and insulation. This rolling contact is not likely to wear and will follow any irregularity or depression of the heads 17 of the bolts or terminals and also is less likely to produce sparks and burning of the electrodes.

What we claim is:

1. In a timer for electric ignition devices, a rotative shaft having a socket at its inner end and an attaching socket at its outer end, a transverse tubular head having a reduced portion formed to provide a stem for engagement in the inner socket of said shaft and also having a longitudinal slot, a yoke having a stem slideable in the head, a pin in the yoke and slideably engaging the slot in the head, a spring encircling the stem of the yoke and engaging the latter to move the same outward, a rolling contact journaled in the yoke,

an insulating ring surrounding the head and traversed by the rolling contact, a casing inclosing the head and ring, means for adjusting the case about the axis of the shaft, radial bolt shaped terminals extending through the ring and engaged by the rolling contact, and nuts on the outer end of the terminals to connect wires thereto and to hold the parts in place.

2. In a timer for electric ignition devices, a rotative shaft having a socket at each end, a tubular head having a stem fitted in the inner socket of said shaft and also having a longitudinal slot, a yoke having a stem slideable in the head, a pin carried by the yoke and slideably engaging the slot in the head, a spring having connection with the stem of the yoke and adapted to force the latter away from the hollow head, a contact carried by the yoke, an insulating ring surrounding the head and traversed by the contact, a casing inclosing the head and ring, means for adjusting the casing about the axis of the shaft, and terminals extending through the ring and casing and having heads at their inner ends embedded in the ring and engaged by said contact.

In testimony whereof we affix our signatures in presence of two witnesses.

FRANCIS C. MASON.
GUY L. SINTZ.
